SALT AND PEPPER SHAKER SET

Jerry B. Rodgers and Margherita H. Rodgers,
Des Moines, Iowa

Application June 2, 1955, Serial No. 36,342

Term of patent 14 years

(Cl. D44—22)

Fig. 1 is a front perspective view of a salt and pepper shaker set showing our new design, and

Fig. 2 is a rear view thereof.

We claim:

The ornamental design for a salt and pepper shaker set, substantially as shown.
